UNITED STATES PATENT OFFICE

CLARENCE E. JULIN, OF JAMESTOWN, NEW YORK

WINDOW CONSTRUCTION

Application filed February 14, 1931. Serial No. 515,852.

This invention appertains to new and useful improvements in building constructions, and more particularly to a novel window construction.

5 The principal object of this invention is to provide a composite window construction involving sashes for general use, a knock-down window screen and knock-down storm window or shutter.

10 Another important object of the invention is to provide a window construction wherein disappearing screens and storm units are provided.

Still another important object of the invention is to provide a composite window construction wherein the different mobile units can be regulated in an easy and convenient manner.

These and other important objects and advantages of the invention will become apparent to the reader of the following specification and claims.

In the drawings:

Figure 1 represents a vertical sectional view through the window construction.

Fig. 2 represents a diagrammatic view of the window construction, with the screen unit in used position.

Fig. 3 represents a diagrammatic view 30 closing the storm window in used position.

Fig. 4 represents a diagrammatic view disclosing the sashes for general use in closed position and showing the screen and storm units removed.

35 Fig. 5 represents a fragmentary horizontal sectional view through the sashes, screen and storm units, and corresponding weight.

Fig. 6 represents a fragmentary enlarged view in section, disclosing the weights of the 40 screen sections.

Fig. 7 represents a fragmentary edge elevational view of the storm unit.

Fig. 8 represents a fragmentary edge elevational view of the storm unit with the connecting link removed.

45 Fig. 9 represents a perspective view of one of the link slide blocks.

Fig. 10 represents a fragmentary edge elevational view of the storm unit with the link removed.

Fig. 11 represents a side elevational view of one of the plate units.

Fig. 12 represents a fragmentary detailed sectional view of one of the storm window sections.

55 Fig. 13 represents a fragmentary detailed sectional view disclosing the guide for the screen unit.

Fig. 14 represents a fragmentary detailed sectional view of the supplemental guide 60 means for the screen unit.

Fig. 15 represents a fragmentary detailed sectional view disclosing the guide means for the storm unit.

65 Fig. 16 represents a fragmentary detailed sectional view of the supplemental guide means for the storm unit.

Fig. 17 represents a fragmentary detailed sectional view of the storm unit.

70 Fig. 18 represents a fragmentary detailed sectional view of the screen unit.

Fig. 19 represents a fragmentary front elevational view of the storm unit.

75 Fig. 20 represents a perspective view of one of the latch bolts.

Referring to the drawings wherein like numerals designate like parts, it can be seen in Fig. 4, that numeral 5 generally refers to a window construction which includes the upper compartment 6 for the novel storm 80 unit, and the lower compartment 7 for the novel screen unit.

This window construction also includes the vertically extending side compartments 8-8 to accommodate the counter-balancing 85 weights of the sashes 9 and 10, as well as the sections of the storm and screen units.

As is shown in Fig. 5, the construction of one side compartment, and its associated slides and weights is represented, and it is to 90 be understood that the other side compartment with its adjunct is substantially identical in construction.

Still referring to Fig. 5, it can be seen that the side compartment has a shell generally 95 referred to by numeral 11 installed therein. The shell 11 is pressed or stamped to form inwardly projecting vertically extending guide ribs 12 and 13, and secured to the inner side of this shell 11 are the guide ribs 100

14 and 15. The inner side wall of the shell 11 is indentured to provide the slideways 16, 17, 18 and 19, each of which is provided with an inwardly projecting guide rib at 20.

5 As is clearly shown in Fig. 5, sliders 21 are interlocked in the slideways 16 and 17 so as to be slidable along the sash, and detachably connected to the sliders are the window sashes 9 and 10 hereinbefore referred to.

10 As is clearly shown, each of these sashes is made up of a hollow frame 22 provided with an inwardly disposed shoulder 23 against which the pane can be disposed. The frame is provided with an opening through 15 which the keys 24 can be disposed for securing the pane in place prior to the placement of the cement or putty 25.

In the remaining two slideways 18 and 19, is slidably disposed the links 26 connecting the blocks. These links and blocks are employed not only with the storm window unit generally referred to by numeral 28, but also with the screen unit generally referred to by numeral 29. The window panes of the storm unit sections are secured to their section frames in the same manner as are the panes in the window sashes 9 and 10. However, the screen 30 in each of the screen sections is secured as at 31 in any suitable 30 manner to its corresponding section frame.

At is shown in Fig. 18, the side edges of the sections are slotted so as to receive the slide blocks 32, which are flanged as at 33 to prevent displacement from the slots. Links 34 serve to connect corresponding screen sections together, and each of these links 34 is provided with slets 35 as are the links 24, of the storm unit. (See Fig. 7). Headed screws 36 extend through the slots 35 and into the blocks 32, thus providing slip connections between the ends of the links and the corresponding blocks 32.

45 In the slots of the screen sections are the slide blocks 37 and 38, located between complementary blocks 32-32, the upper block 37 being provided with an outwardly extending tongue 39 as shown in Fig. 18. Each of these blocks 37 and 38 carries a roller 40.

50 The storm unit is constructed in a similar manner, excepting that the upper slide block 37 is not provided with the tongue whereas the lower slide block 38' is provided with the tongue 39'.

55 For permitting the removal of the sash sections of the storm unit, as well as the sections of the screen unit and the sashes 9 and 10 from their corresponding slides, latch means such as is shown in Fig. 17 is 60 employed. This latch means includes a pair of latch bars 41 for each sash section, each of these latch bars being provided with an obliquely disposed head 42 for disposition through registering openings in the corresponding section frames and slides 21. A

70 handle 43 is provided on each end of each section and between the ends of these handles and the corresponding latch bars 41 are the links 44. A spring 45 is provided on each latch bar for normally maintaining the same in a projected position connecting the corresponding section with its slide 21. Suitable guide means can be provided for the latch bars 41.

75 In the upper storm unit compartment 6 are the upper tracks 46 upon which the rollers 40 of the storm unit sections ride. The lower rollers 40 ride upon the lower inclined tracks 47. In the lower screen compartments 7 are the upper track guides, each of 80 which is made up of a pair of closely spaced rails 48 between which the upper rollers 40 of the screen unit sections ride. The lower rollers 40 of the screen unit sections ride under the lower track 49, located adjacent 85 the lower portion of the compartment 7. In each of the compartments 6 and 7 is a thrower arm 50 of substantially L-shape and rockably supported at its heel portion, as at 51. The elongated portion of the arm 50 is bulged at its inner side, and which point is urged against the corresponding unit section.

90 Although only one arm is represented in each compartment in Fig. 1, it is to be understood that two of such arms are to be provided in each compartment, and obviously as each section is moved into its compartment and bears against the foot portion of the arm 51, the elongated portion will throw 95 against the section to shift the same inwardly and onto the guide rails.

95 A spring is associated with each of the arms 51 for maintaining the same normally removed from the sections. Suitable handle 100 means can be provided on the first section of both of the storm and screen units so that the same can be easily extracted from their corresponding compartments.

105 As is shown in Fig. 4, slidable between the 110 ribs 12 and 13, and the ribs 20-20 are the weights 52, each of which is provided with a channel bar 53 secured to each end thereof for receiving the aforementioned rib. In this manner, the weights are vertically slid- 115 able and are connected over the pulleys 54 by means of the cables 55 to their corresponding sections 9 and 10.

120 The counter-balancing means for the sections of the screen unit, is different from that of the general sashes 9 and 10 and is clearly represented in the diagrammatic view in Fig. 2. As is clearly shown in Fig. 2, each side compartment 8 is provided with a vertically extending rib 56 divided into separate sections decreasing downwardly in width so as to provide outstanding shoulders 57.

125 Slidable between these ribs 56 and the corresponding ribs 20 is the train of weights 130
